(57) **CLAIM**

The ornamental design for a compact toaster grill, as shown and described.

DESCRIPTION

FIG. 1 is a front perspective view of a compact toaster grill showing my new design.

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The article is depicted with a front located and separate drip tray, which does not form part of the design.

The broken lines showing a drip tray in FIGS. 1-3 and FIGS. 5-8 is for illustrative purposes only and form no part of the claimed design.
